(57) **CLAIM**

The ornamental design for a drawer system housing a kitchen module, as shown and described.

DESCRIPTION

FIG. 1 is a front view of a drawer system housing a kitchen module showing our new design;

FIG. 2 is a right side view thereof;

FIG. 3 is a top view thereof;

FIG. 4 is a left side view thereof;

FIG. 5 is a front-right perspective view thereof; and,

FIG. 6 is a front-right perspective view thereof showing the drawer system in an alternate open state.

The broken lines depicting the remainder of the drawer system housing a kitchen module form no part of the claimed design.

1 Claim, 6 Drawing Sheets
